(57) **CLAIM**

The ornamental design for a freestanding blanking panel, as shown and described.

DESCRIPTION

FIG. 1 is a front perspective view of a freestanding blanking panel showing our new design;

FIG. 2 is a detail view of a portion thereof, as identified in FIG. 1;

FIG. 3 is a rear perspective view thereof;

FIG. 4 is a front view thereof;

FIG. 5 is a rear view thereof;

FIG. 6 is a right side view thereof;

FIG. 7 is a left side view thereof;

FIG. 8 is a top view thereof; and,

FIG. 9 is a bottom view thereof.

The broken lines shown in the drawings illustrate portions of the freestanding blanking panel that form no part of the claimed design.
